UNITED STATES PATENT OFFICE

FORD L. SABIN, OF CLEVELAND HEIGHTS, OHIO, ASSIGNOR TO THE WELLMAN ENGINEERING COMPANY, OF CLEVELAND, OHIO, A CORPORATION OF OHIO

INGOT TURNING MACHINE

Application filed September 18, 1926. Serial No. 136,232.

This invention relates to an ingot turning machine adapted particularly for use with so-called continuous ingot heating furnaces.

It is customary to heat ingots by placing them in one end of a long furnace and gradually moving them along the furnace until they reach the opposite end, the ingots at this point having reached a sufficiently high temperature to enable them to be worked in suitable machines, such as seamless tube forming machines. The furnace is provided on one or on each of its sides with doors, and the ingots are moved successively and progressively along the furnace by a bar which is inserted in a door and then swung laterally about a pivot point so as to advance the ingot to a position such that it can be reached by the bar when inserted through the opening of the adjoining door.

The ingot turning bar has heretofore been supported on a machine movable along a track parallel to the side of the furnace, but these machines have not been satisfactory because the bar, when swung laterally to advance an ingot, would strike and damage the furnace structure around the door opening, making it necessary to frequently repair the furnace.

The object of the present invention is to provide an ingot turning machine having a turning bar so supported and moved that the bar can be inserted in the opening of any one of the doors and be given a full swinging stroke to advance the ingot without liability of engaging or injuring the door frame or furnace structure around the door opening.

The machine embodying my invention includes a machine body or carriage which is designed to travel along a track at the side of the furnace, and a turning bar is mounted on an upper carriage to move in an arc-shaped path, the center of movement being at or adjacent the door opening, making it possible to swing the bar through a considerable angle without engaging the furnace walls around the door opening.

The invention may be further briefly summarized as consisting in certain novel combinations and arrangements of parts and details of construction which will be described

in the specification and set forth in the appended claims.

In the accompanying sheets of drawings, Fig. 1 is a diagrammatic view illustrating the furnace in section and showing conventionally the ingot turning machine, this view indicating the movement of the bar and of the carriage which supports it in advancing an ingot one step in the furnace; Fig. 2 is a top plan view of the machine, with a portion of the furnace in section; Fig. 3 is a side view of the same; Fig. 4 is a plan view of the lower carriage or body portion of the machine; Fig. 5 is a side view of the lower carriage as viewed from the front of the furnace; Fig. 6 is an enlarged end view of the lower carriage; Fig. 7 is a sectional view through the ram which carries the turning bar and illustrates part of the supporting means for the ram; Fig. 8 is a side elevation of a part of the upper carriage illustrating the rocker for the ram; Fig. 9 is a transverse sectional view substantially along the line 9-9 of Fig. 8; and Fig. 10 is a fragmentary sectional view substantially along the line 10-10 of Fig. 2.

Referring now to the drawings, I have illustrated at 10 a portion of a continuous ingot heating furnace in connection with which my improved machine has special utility. The ingots, some of which are shown at 11, are introduced at one end of the furnace and are progressively moved along the furnace and finally delivered from the opposite end. Heat is supplied to the furnace in any suitable way, and when the ingots are removed from the far end of the furnace they are delivered to a suitable ingot handling and working machine such as a tube machine.

The furnace is provided along one or both sides with a series of rather closely arranged vertical doors 12 through which a bar is inserted to progressively and successively move the ingots forward. If two rows of ingots are handled by the furnace at the same time, both sides of the furnace will be provided with these doors, as indicated in Fig. 1, and in such cases an ingot turning machine such as constitutes the subject matter of this in-

vention may be provided at each side of the furnace or the same machine may be used on both sides.

The machine travels along the rails 13 of a track which extends parallel to the side of the furnace for its full length, and a suitable distance therefrom. The machine includes a lower carriage or body portion 14, the frame of which may be formed of a suitable casting or may be built up of structural material. It is provided with wheels 15 which run upon the rails 13, and is equipped with a traversing motor 16 geared to the track wheels 15. Additionally, the lower front part of the frame is preferably provided with guide rollers 17 (see Fig. 6) which engage opposite sides of the ball of the front rail 13. These guide rollers, as well as others employed in the machine and hereinafter referred to, are preferably adjustable to compensate for wear, the adjustability being preferably provided by supporting the rollers on vertically disposed shafts, designated 18 in Fig. 6, having eccentric bearing portions for the rollers. To provide for holding the rollers in any adjusted position, the upper ends of the shafts are preferably provided with laterally projecting members 19, each of which can be fastened in adjusted position by a locking pin adapted to be inserted in any one of a series of openings provided in said member or in the structure immediately beneath it.

On the top of the frame of the lower carriage two curved track rails 20 and 21 are provided, which, it will be observed, are curved on arcs of concentric circles, the center of which is forwardly of the machine, and, for a purpose to be explained presently, the center lies in the vertical longitudinal plane intersecting the front wall of the furnace at about the center of the door openings. That is to say, when the lower carriage of the machine is positioned opposite any one of the door openings 12, the center of the two arc-shaped tracks 20 and 21 will be at substantially the center of that particular door opening.

Adapted to travel on the rails 20 and 21 is an upper carriage consisting of a suitable frame 22 carrying a pair of rear wheels 23 which ride on top of the rear curved rail 21, and a pair of front wheels 24 which ride on the top of the front curved rail 20. Suitable guide rollers will be provided to keep the wheels of the upper carriage on the rails 20 and 21, these usually consisting of two pairs of rollers 25 engaging opposite sides of the front rail 20. These rollers, or at least one of each pair, are adjustably mounted like the guide rollers 17 previously described.

This upper carriage, which supports the turning bar in a manner to be explained, is adapted to be moved laterally over the arc-shaped tracks 20 and 21 by a motor 26 car-

ried by the frame 22 of the upper carriage, this motor having its shaft connected by a worm and worm wheel gearing 27 (see Fig. 2) to a vertical shaft 28 (see Figs. 2 and 10) having at its lower end a pinion 29 engaging an arc-shaped rack 30 provided on the front side of the front curved rail 20. The lateral movement of the upper carriage imparts to the turning bar, which is illustrated at 31, the lateral movement necessary to advance an ingot by rolling it forward one step, as indicated at the righthand side of Fig. 1.

This turning bar is capable of other motions in addition to the lateral swinging motion imparted to it by the travel of the upper carriage on the track rails of the lower carriage. These additional movements include an in-and-out or endwise motion which enables the bar to be retracted so as to be clear of the furnace (note the lefthand side of Fig. 1) and to be inserted forwardly into any of the door openings. Additionally, the turning bar can be swung vertically and turned about its longitudinal axis, the vertical swinging movement and the turning of the bar about its longitudinal axis being utilized at times in separating two adjacent ingots should they come in contact with each other and become temporarily fused together.

Generally, a series of turning bars are provided so that if a bar becomes unduly heated it can be replaced with a cold bar, and, accordingly, provision is made for detachably connecting the bar to the part which immediately supports it. A suitable mode of connection is illustrated in Fig. 7, where the rear end of the bar is shown attached to a supporting member consisting, in this instance, of a hollow spindle 32 which is rotatably supported to turn about its longitudinal axis in a hollow ram 33 which is supported for endwise motion by a series of top rollers 34 and bottom rollers 35 (see Fig. 8) carried by a housing consisting of a hollow casting in the form of a rocker 36 which is provided with oppositely disposed trunnions 36a and 36b (the latter being formed in sections for convenience of assembly) which trunnions are supported in bearing portions 22a of the frame 22 of the upper carriage (see Fig. 9). A part of the ram-supporting rollers carried by the rocker 36 may be adjusted to compensate for wear like the adjustable track engaging rollers heretofore referred to.

For the purpose of moving the ram with the turning bar in endwise direction toward and from the furnace, a motor 37 is provided on the frame of the upper carriage (see Fig. 2) and this motor has its shaft connected by a worm and worm wheel gearing 38 (see Fig. 9) to a shaft 39 extending centrally through the trunnions of the rocker 36 and provided with a pinion 40 (Figs. 7 and 9),

engaging a rack 41 provided on the lower side of the ram 33.

For the purpose of swinging the turning bar and ram vertically, a motor 42 is provided on the frame of the upper carriage (Fig. 2) this motor having its shaft connected by worm and worm wheel gearing, indicated at 43 in Fig. 2, to a shaft 44 which is connected by spur gearing, indicated at 45 in Fig. 2, to a shaft 46 (Fig. 8) carrying an eccentric 47 engaging a shoe 48 mounted in a pair of guideways 36c formed on the rear end of the rocker 36.

For the purpose of turning the bar 31 and spindle 32 about the axis of the latter I have in this instance shown at the rear of the ram a handwheel 49 which is connected by worm gearing 50 (see Fig. 7) and by a spur pinion 51 to a gear 52 secured on the rear end of the spindle 32 to which the turning bar is attached. If desired, the turning bar and spindle may of course be turned by a motor, but manual operation through the medium of a handwheel with suitable reduction gearing 25 is now thought preferable.

In the use of the ingot turning machine described above, the base or body portion of the machine will be positioned in front of a particular door opening, then the ram is moved 30 forwardly so that the turning bar will be inserted in the door opening behind one of the ingots to be moved, the upper carriage, ram and bar then being in the position indicated by full lines at the righthand side of 35 Fig. 1. Then by moving the upper carriage laterally to the dotted line position, the ingot will be advanced to the dotted line position of the ingot as shown in Fig. 1. During this lateral movement of the upper carriage, the 40 bar swings about an axis forwardly of the machine at or about the center of the door opening, as indicated in Fig. 1.

This operation is generally repeated at each door opening so that the ingots of the 45 entire series are successively moved forward.

While I have shown the preferred construction, I do not desire to be confined to the precise details shown, but aim in my claims to cover all modifications which do 50 not involve a departure from the spirit and scope of the invention.

Having thus described my invention, what I claim is:

1. In combination with an ingot heating 55 furnace having a door in the side thereof, an ingot shifting machine comprising a curved track, the center of curvature of which is substantially in the plane of the said door, a carriage movable bodily upon said curved 60 track and supported exclusively thereby, said carriage being provided with a turning bar which is insertible through said door and which swings with the carriage.

2. In a machine of the character described, 65 a carriage adapted to move in an arc of a

circle, an ingot moving device comprising a tubular ram, means for supporting said ram upon said carriage and for moving it longitudinally with respect thereto, a spindle supported within said ram for rotation about its own axis, and an ingot moving bar removably secured to the forward end of said spindle. 70

3. In a machine of the character described, a frame, an arcuate track comprising a pair of concentric rails mounted upon said frame with their axis of curvature forward of the frame, a carriage supported solely by said track, anti-friction thrust bearings mounted upon said carriage to turn on vertical axes 75 and bear upon the forward one of said rails, and a bar mounted upon said carriage with its axis intersecting said axis of curvature.

In testimony whereof I hereunto affix my signature.

FORD L. SABIN.
